UNITED STATES PATENT OFFICE

2,407,864

CHAIR BED

Louis Arzt, Bronx, N. Y.

Application May 9, 1945, Serial No. 592,772

4 Claims. (Cl. 5—13)

1

This invention relates to chair beds and in particular to one in which a full sized bed of maximum length can be folded.

A particular object of the invention is to provide a bed structure that can be folded into a settee type chair in the lowest position consistent with comfortable use of the chair as such. The problem of providing a full length bed structure that can be folded lengthwise for positioning in the bottom of a chair at the lowest point involves the use of inner, middle and outer sections that are folded relatively to each other in the most compact manner possible and which can be, by the folding operation, lowered to seat in the bottom of the chair frame. The invention also contemplates ease of folding the sections by the arrangement of the parts and connections thereof and provides for a longitudinal motion of the partly folded structure that will automatically lower the folded assembly into place in the bottom of the chair frame. It is a feature of the invention that the least number of parts are employed that are consistent with strong and durable structure and easy folding operation, the arrangement of the parts being such that they fold compactly with a minimum of preliminary adjustment, and when incorporated in the chair in folded position conceal the fact that a bed is also part of the chair structure.

With these and other objects in view, the invention comprises certain constructions herein-after described and then particularly pointed out in the claims and a preferred form of my invention is illustrated in the accompanying drawings, in which:

Figure 1 is a section in side elevation taken through a chair frame and showing the bed structure in open position in full side view,

Figure 2 is a similar view showing the bed structure in first fold position in full lines and second fold position in outline,

Figure 3 is a view similar to Figure 1 showing the bed structure in a position it would assume during sliding and lowering movement to place it in the chair frame,

Figure 4 is a view similar to Figure 3, but showing the bed structure completely folded into the chair frame to provide a seat,

Figure 5 is a perspective view of a detail of the bed structure as viewed at the line 5—5 on Figure 2,

Figure 6 is a side view of an operating detail associated with a fold section shown enlarged, and

Figure 7 is a section on the line 7—7 of Figure 6.

2

Referring to the drawings in detail, 10 indicates chair ends shaped to provide arm and back parts 11 and 12 respectively, which are joined by suitable cross pieces 13 placed conveniently to give a substantial chair frame. The mattress supporting frame of the bed is made in the usual manner with L-shaped rails or bars between which is stretched the spring panel for holding the mattress. The spring and rails are indicated 10 by the numerals 14 and 15 respectively and the rails and spring assemblies are arranged to provide the relatively foldable sections, progressing outwardly from the chair, identified as the inner section 16, middle section 17, fold section 18 and outer section 19. The inner frame section 16 carries corner foot-pieces 20 which are pivoted as at 21 to brackets 22 secured to the chair ends 23, and the inner end of the section is reinforced by the cross bar 24. Both sides of the bed structure are identical and hence only one side will be referred to, no plan view being deemed necessary as the art shows that the levers, legs and frames are suitably bent to clear each other in folding relation, and these structures and their 25 method of assembly are well known by those skilled in the art.

The middle section 17 is pivoted as at 25 to the section 16 and is supported in relatively swinging relation to the chair frame by the swing 30 lever 26, hinged to the section 17 as at 27 and pivoted to a frame plate 28 as at 29. The lower end of the lever 26 is connected by a spring 30 to an ear 31 formed on said plate 28, the plate forming part of a reinforce structure for the chair and including the cross braces 32 and 33, which support the folded bed structure when it is compacted into the chair frame as shown in Figure 4. A stop 35 on middle section 17 also acts as a rest for the outer folded section as shown 35 in Figures 2, 3 and 4. The middle section 17 is pivotally connected at its end with the outer section 19 through the medium of the fold section 18, the pivot points being indicated as at 36 and 37, which permit the outer section to be 40 folded parallel to the middle section 17 and thereabove to provide a compact and sturdy seating structure when the parts are folded into the chair frame.

One of the features of my invention is the arrangement of the front chair panel, strip and seat frame on the folding sections so that they will be folded into place without any attention on the part of the operator and to this end, the fold section 18 is provided with a depending fixed leg bracket 40 (Figures 6 and 7) to which the rear leg

is eccentrically pivoted as at 42, the leg 41 being pivoted as at 43 at its upper end to the outer end of a rear leg lever 44 which is pivoted as at 45 to the middle section 17. The fold section is relatively narrower than the sections 17 and 19 which it joins and it has pivoted thereto as at 46 a forwardly extending front leg lever 47 which is pivoted as at 48 to the upper end of a front leg 49 pivoted as at 50 to the outer section 19. Both legs, the rear leg 41 and the front leg 49 firmly support the extended portions of the bed structure when the same are open for bed use. The outer section 19 supports, through a link 52, a rectangular seat frame 53, which carries as indicated in outline in Figure 1, a seat cushion C, and which seat frame is fixed to the edge of a front strip 54 which in turn is hinged as at 55 to the upper edge of a panel strip 56 fixed to and carried by the rear leg 41. The strip 54 and panel 56 together constitute a closure to conceal the bed structure when the same is folded into the chair, as shown in Figure 4. The outer end of the outer section 19 (Figure 5) is closed by the cross brace 57, the same being fixed to a corner piece 58 at each end of section 19 to which is pivoted a head piece frame 60. The head piece comprises the pillow supporting strips 61 and 62, to the latter of which a spring is secured to connect the head piece and the brace 57. The spring 63 acts to maintain the head rest structure in either its open position as in Figure 1 or in its folded position as at Figure 5 because the side brackets 64 through which the strips 61 and 62 are pivoted with respect to section 19 as at 65 swing the spring 63 past the pivot center 65 which joins the head piece frame to the corner piece 58.

A mattress M is indicated in outline and starting with the bed fully open as in Figure 1, the first folding movement results in the bed outer section 19 being lifted to the position in full lines in Figure 2. This motion closes the front leg and swings the seat frame 53 about its hinge 55 until the strip 54 is horizontal. The second folding movement begins automatically because the fold of the leg 49 prevents further hinged movement of the outer section relatively to the fold section 18 and hence continued folding pressure on the outer section 19, results in the folding of the fold section 18 about the pivot 36 to position the parts as shown in outline in Figure 2 and until the corner piece 58 rests on the stop 35 through the medium of engagement of shoulder 66 in piece 58 with the turned over top edge or end of the stop 35. This second folding movement automatically causes the rear leg lever 44 to swing the rear leg 41 to a position parallel to the fold section 18 and to hingedly align the panel strip 56 and the front strip 54 and bring the seat frame 53 down into resting contact with the outer section 19 and, as shown in outline in Figure 2, atop thereof. The folded structure is supported by the swing lever 26 and the bracket 22 and when further pushed in closing movement, swings upwardly and inwardly as shown in Figure 3 by the action of the lever 26 operating about its pivot point and against the resistance of its associated spring 30 which assists in the opening movement of the structure because when the bed has been folded the spring is held under tension. Movement of the swing lever 26 is permitted by the break of the inner section 16 and the middle section 17 at their pivot point 25 and the folding movement of the parts is ac-

complished by the swinging of the inner section 16 about its supporting bracket 22 as at 21.

The folded structure rests in the bottom of the chair as shown in Figure 4 and the parts are so lowered that the seat cushion C is low and comfortably positioned to permit the legs to rest comfortably on the floor, this feature removing one of the objections to the use, heretofore of sufficient structure to make a folding bed that could be made long enough to permit sleeping with the feet inwardly of the chair, so that two persons could find enough room in the bed and considerably more than could be afforded by the prior structures that made sleeping lengthwise of the chair necessary.

My improved folding bed structure can be incorporated in any suitable chair or table frame and its use in connection with an article of furniture is an example of how it may be employed.

My invention is not to be restricted to the precise details of construction shown since various changes and modifications may be made therein without departing from the scope of the invention or sacrificing the advantages derived from its use.

What I claim is:

1. In a chair bed, in combination, a chair frame, an inner bed section pivoted in said frame, a middle section pivotally connected to said inner section and to said chair frame, an outer bed section, a fold section for connecting said middle and outer sections in relatively foldable relation, a rear leg, a bracket to which the rear leg is eccentrically pivoted the bracket being secured to said fold section, and a leg lever connecting said middle section and said rear leg for folding the latter when the foldable section is folded with respect to said middle section.
2. In a chair bed, in combination, a plurality of relatively foldable bed sections pivoted to each other and to said chair frame, said sections including a fold section, a bracket fixed to said fold section, a leg pivoted to said bracket, a closure strip pivotally associated with said leg, a chair seat frame secured to said strip, a link connecting the seat frame with another of said bed sections, a leg operating lever pivoted to another of said foldable bed sections and to the leg for folding the same when the sections of the bed are relatively folded, and said closure strip being swung to closure forming position and moving said seat panel to position against one of bed sections by the movement of said link when the bed sections are fully folded relatively to each other.
3. In a chair bed, in combination, a chair frame, inner and middle bed sections pivotally mounted in said frame, a stop on said middle section, an outer section, a fold section for pivotally joining said outer and middle sections, a front leg pivoted to said outer section, a rear leg pivotally associated with said fold section, a front leg operating lever pivoted to the fold section for folding the front leg when the outer section is folded relatively to said fold section, and a rear leg lever pivotally connected to the rear leg and the middle section for folding said rear leg when the fold section is folded relatively to said middle section, and means on the outer section for engaging said stop to limit the folding movement of said sections.
4. In a chair bed, in combination, a chair frame, inner and middle bed sections pivotally mounted in said frame, an outer bed section, a fold section pivotally connecting said middle and outer

sections for allowing fold of said outer section to a position above and parallel with said middle section, a stop on the middle section, a corner piece on the outer section presenting a shoulder for engagement with said stop to support the outer section in folded position, legs pivotally associated with said outer and fold sections, leg operating levers pivotally connected to the legs and to relatively foldable sections whereby on folding movement of said sections the legs are 10 folded, a closure panel attached on one of the

legs, a closure strip hinged to said panel, a seat frame secured at one edge to said strip, a link for pivoting the seat frame with respect to one of the foldable sections, and said seat frame being positioned against said section to which it is linked and said panel and strip being moved to form a closure for the chair frame when the sections of the bed have been fully folded into said chair frame.
